HIGH-PRESSURE GUN FOR GREASE AND OIL

Josef Wagner, Friedrichshafen, Fischbach, Germany

Application September 24, 1957, Serial No. 685,922

Claims priority, application Germany August 2, 1957

8 Claims. (Cl. 222—108)

The invention relates to a high-pressure gun for grease and oil wherein the grease or oil is sucked by means of a piston pump driven by an electric motor out of a container removably attached to the gun housing and is expelled at high pressure, from the nozzle which is closed by means of a spring-loaded non-return valve, by means of the pump piston which, in its forward movement, closes the intake.

It is the object of the invention to develop a high-pressure gun of the aforesaid type in the sense of more complete adaptation to rough service and a high working pressure and to limit the height of the latter by means of a suitable device which is adjustable as required.

The solution of this problem according to the invention consists in that the shaft of the motor, which is flange-connected in known manner to the gun housing, is coupled through a reduction gear to an eccentric which is mounted for rotation on a shaft located in the gun housing, and which rests on the outer periphery of a ball-bearing roller, the journal of which is secured to a preferably bent rocking lever, the free end of which rests against the end face of the pump piston rod which projects into the gun housing, or against the intermediate piston, so that, in this manner, the pump piston, which is constantly restored to its initial position by spring pressure, is reciprocated in time with the speed of rotation of the eccentric.

In the end of the pump cylinder which projects out of the gun housing, there is screwed a pressure-relief valve of which the valve tappet, which is provided with a frusto-conical head and with an axial bore, is urged by plate springs against the valve seating. The force of these plate springs is adjustable by means of a retaining nut which encases the springs and which comprises, at the end remote from the gun housing, bores for discharging the excess lubricant delivered.

Further details of the invention can be seen from the following description of an example of an embodiment explained with reference to the drawing. The drawing represents a longitudinal section through the axis of the pump piston, partly broken away, of the high-pressure gun constructed in accordance with the invention.

The housing of the grease and oil gun, which is constructed like a pistol, is made of die-cast light metal or synthetic material and is given the reference numeral 1. The housing comprises a handle 2 on the inside of which is conveniently mounted a press-button 3 by means of which the driving motor 4, which is flange-mounted on the housing 1 and is only partly shown in the drawing, can be switched on and off. The grease or oil container 5 is screwed into or otherwise secured in an easily detachable manner, to the housing 1 below the nozzle or pressure-relief valve 6 of the gun.

The stub axle 7 of the motor 4, which projects into the housing 1, ends in a pinion 8 which, together with the gearwheel 9 forms a reduction gear. The gearwheel 9 is rigidly coupled to the eccentric 10. The latter is mounted for rotation on the shaft 11 which is fixed on both sides in the housing 1. The eccentric 10 rests on the

outer periphery of a roller 12 which is mounted by means of a ball bearing on the journal 13. This journal is secured to the bent rocking lever 14 which rocks, at its upper end, about the pivot pin 15 secured in the gun housing 1. The free end 14' of the rocking lever 14 rests against the end face of the intermediate piston 16 of the rod of the pump piston 18, which projects into the housing 1.

The spring retainer 17 of the rod of the pump piston 18 rests against the other end face of the intermediate piston 16. The pump piston 18 is guided in the pump cylinder 20 which is located in the gun housing by means of the setscrew 21. The spiral spring 19 rests against the pump cylinder 20 and urges the spring retainer 17 against the intermediate piston 16. The force of the spring 19 ensures that the roller 12, which is mounted for rotation on the rocking lever 14, always bears against the eccentric 10.

When the shaft 7 of the driving motor 4 rotates, the eccentric 10 rocks the lever 14 in clockwise direction in time with the speed of rotation of the motor. This leads to a displacement of the pump piston 18 inside the pump cylinder 20 against the force of the spring 19. The last-mentioned spring restores the pump piston 18 to its initial position each time.

In the end of the pump cylinder 20 remote from the rocking lever 14 there is installed a non-return valve 22, the stem 22' of which is guided in the member 23 screwed into the pump cylinder 20. This member is provided with axial passages for the grease or oil. The non-return valve 22 is urged against its valve seating by means of the spring 24. The spring tension can be adjusted by means of the member 23 which can be screwed backwards and forwards in the axial direction.

In the pump cylinder 20 and in the housing 1 is a suction bore 25 which, through a filter 26, provides a connection between the bore in the pump cylinder 20 and the grease or oil container 5. The suction bore 25 leads to a point in the bore of the pump cylinder 20 which, when the pump piston 18 is displaced into the position nearest the driving motor 4—the suction position—is not yet covered by the pump piston but which is covered thereby during the delivery stroke of the pump piston 18. The pump 18, 20 automatically sucks up the grease or oil from the container 5.

Screwed into the end of the pump cylinder 20 which projects out of the gun housing 1 is a pressure-relief valve 6. With this the maximum permissible working pressure can be adjusted within wide limits—about 100 to 1000 atmospheres. This adjustment is effected by means of the retaining nut 6' which shuts off the interior of the pressure-relief valve 6 from the outside. Mounted in the recess in the nut 6' are the plate springs 33 which are axially displaceable on the valve tappet 31 provided with an axial duct or bore 32 and which urge the frusto-conical head 31' of the valve tappet against the valve seating 34. This pressure is variable by screwing the retaining nut 6' to a greater or lesser extent on the valve seating member.

If the delivery pressure produced by the pump piston 18 exceeds the maximum pressure set by means of the pressure-relief valve 6, then the head 31' of the valve tappet is lifted from its valve seating 34 against the contact pressure exerted by the plate springs 33. The grease or oil delivered is then partially forced past the plate springs 33 and escapes through a by-pass conduit formed by the axial bores 35 provided on the end face of the retaining nut 6', to the outside. In this manner, the pressure of the lubricant reaching the lubricant point through the bore 32 in the valve tappet 31 and the high-pressure tube 37 secured by means of the sleeve 37 to the tappet 31, is lowered.

In the drawing, the lubricant container 5 is constructed in the form of a grease container. Mounted for sliding in the latter is a piston 27 which can be moved up and down by turning the threaded rod 28 provided with a handle 30. A spiral spring 29 resting on the bottom of the container 5 urges the piston 27 against the column of grease lying above the latter. The filling of the grease container 5 is preferably effected as follows:

The empty container 5 is pushed, with the piston 27 advanced, into the bucket containing the supply of grease, and the handle 30 is turned back to the left. In this manner a coherent column of grease, without any air, is sucked into the container 5. The container 5 should then be screwed into the gun housing 1 in such a manner that no air space is formed between the suction head of the gun and the container. The handle 30 of the threaded rod 28, which was previously turned to the left until it abutted against a stop is now turned to the right until it abuts against a stop and thus the piston 27 is pressed against the column of grease under the pressure of the spiral spring 29. In this manner, the grease is reliably pushed towards the suction head of the gun, and during the suction stroke of the pump piston 18 it is sucked through the bore 25 into the pump cylinder 20 and from thence, during the delivery stroke of the piston 18, it is forced through the adjustable pressure-relief valve 6 to the lubricating point.

The high-pressure gun for grease described above may also be used for oil. The grease container is unscrewed and replaced by an oil container equipped with an oil-suction-pipe.

I claim:

1. A high-pressure gun for grease and oil comprising in combination a gun housing, a container for grease or oil detachably secured to said housing, an electric motor flange-connected to said housing, an ejection nozzle, a spring-loaded non-return valve for closing said nozzle, a piston pump for sucking oil or grease out of the container and for ejecting it under high pressure through said nozzle, a reduction gear in said housing, an eccentric coupled through said reduction gear with the motor shaft, a ball-bearing roller against the outer periphery of which the eccentric bears, and a rocking lever secured to the journal of the said roller, the free end of said lever actuating the pump piston reciprocating it in time with the speed of rotation of the eccentric.

2. A high-pressure gun as claimed in claim 1, wherein the rocking lever is a bent lever.

3. A high-pressure gun as claimed in claim 1, wherein the free end of the rocking lever bears against the end face of the pump piston rod projecting into the gun housing.

4. A high-pressure gun as claimed in claim 1, wherein the free end of the rocking lever bears against the end face of an intermediate piston on the pump piston rod projecting into the gun housing.

5. A high-pressure gun as claimed in claim 1, wherein the pump piston when reciprocating is restored at each stroke to its initial position by spring pressure.

6. A high-pressure gun as claimed in claim 1, characterised in that screwed into the end of the pump cylinder projecting out of the gun housing is a pressure-relief valve of which the valve tappet, which is provided with a frusto-conical head and an axial bore is urged against

the valve seating by plate springs the spring tension of which is adjustable by means of a retaining nut which encloses the springs and which comprises, on the end face remote from the gun housing, axial bores for discharging the excess lubricant delivered.

7. A high-pressure gun having a gun housing, for use in discharging material such as grease and oil from a container at high pressure through and out of a nozzle, said gun having a housing, said container being removably connected to said housing, the combination of an electric revolving motor built into said housing, a reciprocating piston pump connected to said housing and adapted to be disposed externally of said container and having an inlet opening communicating with said container, the piston of said pump being oscillatable and spring biased towards a retracted suction position, transmission means between said electric motor and said piston operable for propelling said piston periodically forwardly into a pressure position comprising a revolvable eccentric cam driven from said motor, a bell crank lever having one arm journalled in said housing, a cam follower connected to said lever and driven by said eccentric cam and including an anti-friction bearing disposed substantially at right angle to the axis of said eccentric cam, the other arm of said lever being in driving connection with said piston, said piston being actuatable to close said opening during the forward stroke, and a rigid conduit structure connected to said housing and supporting said nozzle defining a conduit extending between said nozzle and said pump and including a pressure relief valve for said nozzle, whereby said eccentric cam will impart periodic impulses to said cam follower and said lever will transmit these impulses to said piston impelling the piston periodically forwardly and the piston will be retracted by said spring bias during the intervening time intervals, to pump material out of said container into said conduit and through said nozzle.

8. In a high-pressure gun, as claimed in claim 7, said pressure relief valve comprising a valve seat formed in said conduit, a tapered valve head movable to and from a valve closing position on said valve seat and having an internal bore, resilient means urging said valve head towards said valve seat, whereby normally said valve head will engage said valve seat and the bore will conduct the material and, respectively, upon the occurrence of excess pressure said valve head will be lifted by the material off the seat, said conduit structure including means establishing a by-pass duct for the excess material when said valve head is lifted off the seat, and means operable for adjusting the force of said resilient means.
